In Germany January 7, 1933

4 Claims. (Cl. 226—5)

This invention relates to a device for reversing cigarettes and similarly shaped articles of manufacture when packing same, and it has for its object certain modifications of or additions to the device forming the subject matter of U. S. Patent No. 1,787,901 issued January 6, 1931.

In accordance with the invention according to the aforesaid U. S. patent, a stop or the like is provided in conjunction with the cigarette feed device, which stop can be adjusted both while at rest or when in operation. In the latter position, this stop comes to rest against the lower or upper edge of the articles placed transversely in the feed so that during the movement 10 of the feed device in relation to the stop, the articles will be turned over.

The device above referred to has been found unsuitable in the case of high-speed machines. In this case the impact of the cigarettes against 20 the guides is rather violent, with the result that the cigarettes are either damaged or are even jerked out of the feed device, or become wrongly placed on it.

The object of the present invention is to remedy 25 this drawback and to provide a device which while operating according to the principle of the aforesaid patent does not present the above-mentioned disadvantages by reason of the fact that the guides or stops which effect the turning of 30 the cigarettes accompanying the cigarette for a certain portion of its travel and act gradually upon it during its travel, that is to say, move the cigarette slowly from the flat position into the upright position and possibly even beyond it 35 into the reverse flat position. The movement of the turning guides or stops jointly with the continuously advancing cigarettes and the gradual entry of the guide into the path of the cigarette can be effected in various ways. For example, 40 the guide, operated by a crank drive, can execute a movement along with the cigarette and a movement against the cigarette; preferably however, the stops are arranged on a revolving conveyor unit which travels forward at, for example, the 45 same speed as the cigarettes to be turned, and in the same direction, having simultaneously imparted to them a movement at, for example, right angles relative to this direction, that is to say, transversely to the path of the cigarettes.

50 Reference is made to the accompanying drawings which illustrate one example of the invention, and in which:

Fig. 1 is a side view showing more or less diagrammatically the relative parts of the device,

Fig. 2 is a side view thereof,

Figs. 3, 4 and 5 illustrate the method of operation of the device on a somewhat enlarged scale with the turning pins in their different positions.

In the drawings, 1 indicates a conveyor designed in the usual manner, which is provided with teeth and cavities arranged between the latter for receiving the cigarettes. On this conveyor, the cigarettes are fed in the condition 10 in which they are taken from the stack, that is to say, partly with the seam at the top and partly with the face at the top, and they all have to be turned into the face-up position. For this purpose the conveyor, which runs on rails 15 2 over a table 3, is connected either on one side or on both sides to a revolving disc 4. The disc rotates round an axis 5 mounted on a support 6 which is arranged on the table 3. The disc 4 is provided with a concentric circle of 20 bores in which pins 7 are rotatably mounted. These pins carry at one end, that is to say on that nearest to the chain 1, discs 8 from the inner face of each of which projects an eccentrically placed pin 9.

Secured to the opposite end of each pin 7 which projects from the disc 4, are rings 10, each of which carries two radially located pins or lugs 11 and 12 provided with an oblique face. Between the rings 10 and the disc 4 brake springs 13 are inserted, which are intended to maintain the position of the pins 7 in the bores, once it has been adjusted. The disc 4 itself is provided upon its periphery with teeth 14 meshing with a driving pinion, not shown in the drawings. The 35 disc is thereby caused to rotate continuously in the direction indicated by the arrow in Fig. 1, and at such a peripheral speed that the wheel revolves each time by one division, that is to say, a distance equal to that between the pins 7 while 40 the conveyor 1 has moved toward by one division, likewise in the direction of the arrow.

The pins 7 can be set by means of the two lugs or pins 11 and 12 in two different positions. In one position, in which the centres of the pins 9 and the centres of the pins 7, lie upon the same circle, the pins 9 when moving past the chain 1 pass between two cigarettes, that is to say they are situated each time at the point where the 50 tooth of the chain is to be found. If, however, the pins 7 are turned in such a way that the pins 9 are turned from the above mentioned position towards the centre of the disc 4, then the pins pass through the gap in chain 1 and thereby act 55

upon the cigarette and turn the latter. This action is shown in Figs. 3-5. In Fig. 3 the position is shown in which the pin 9 is neutral or ineffective. It can be seen that it passes by the tooth 5 of the chain, that is to say, it passes through between two cigarettes. The next position of disc 8 with pin 9 is shown in the dotted line in Fig. 3. Thus the cigarette will remain in the position in which it is.

- 10 In Fig. 4 the pin 9 is shown turned into the working position. At the same time, the neutral position of the pin is indicated by a dotted line. It can be seen that the pin 9 in the position indicated by a full line must engage with the cigarette, viz. with the left edge of the cigarette, when the disc 8 continues to move on the circle shown by the dot and dash line, and passing through the centres of pins 7. It will thereby turn the cigarette in clockwise direction, and 15 immediately the disc 8 has assumed the position shown by dotted lines in Fig. 4, the pin has turned the cigarette upwards in the manner shown by this illustration.

Fig. 5 illustrates the same adjustment as Fig. 4. 20 In this case, the cigarette has been turned into the vertical position or somewhat beyond same so that it will turn over completely when the pin 9 moves away from it upon the wheel 4 continuing to rotate, thus completing the revolution 25 commenced by the pin. On the other hand, it is also possible to provide special means to prevent the cigarettes from falling backwards, that is to say, stops 21, the lower portion of which preferably consists of rubber or the like, this portion 30 coming into contact with the edge of the cigarette pointing upwards and turning it over completely, if it does not fall over by itself, thus placing it in the face-up position.

The pins 7 are controlled by a lever 15 pivotal- 40 ly mounted at 16. This lever is maintained by a spring 17 against a stop screw 18; at the same time it is in such a position that the lugs 11 on the rings 10 engage with it when the wheel 4 rotates, thus turning the pins 7 in such a way 45 that the pins 9 are brought into the neutral position. In Fig. 1, a pin 11 is shown engaged with the lever 15.

Opposite the lever 15 there is arranged an electro-magnet 19. This magnet is inserted in a circuit which can be closed by a press-button. This 50 press-button is placed within reach of the attendant who is watching the cigarettes travelling past on the chain 1.

Mounted on the pedestal 6 is a further stop 55 22, bent in angular fashion and so arranged that it engages with the inward projecting lugs 12 on the discs 10. As a result of the engagement of the lugs 12 with the stop 22, the rings 10 and thereby the pins 7 are turned in such a way that 60 the pins 9 are brought into the active position, as shown at the left hand side of Fig. 1.

So long as the electro-magnet 19 is not excited the pins 9 turned into the active position by stop 22 will invariably return to their neutral position 65 when moving past the lever 15. If, however, the attendant notices a wrongly placed cigarette, he will close the circuit; the lever 15 is actuated and assumes the position shown by a dotted line in Fig. 2. Consequently it does not return the relative pin 7 into the neutral position so that the pin 9, which is related to it, effects the turning over of this cigarette in the manner described above when its path crosses that of chain 1.

As there is a pin 7 or pin 9 allocated to each 70 cigarette and a certain time elapses between

the electro-magnet 19 being excited and the pin 9 brought thereby into the working position becoming effective, the control must be operated as a cigarette passes a certain point.

This point is characterized in Fig. 1 by means 5 of an inspection device 20. The inspection can take place directly by an operator who, for example, looks down through the tube 20 and observes the cigarettes passing under it. However, provision may also be made for an automatic- 10 electrical control in the form of a photo cell or selenium cell which are controlled in the manner known per se by the different reflections of light issuing from the cigarette, according to whether a non-printed, that is to say, wrongly 15 placed cigarette, or a cigarette provided with an imprint and placed correctly, passes by. The photo cell then controls the circuit exciting the electro-magnet 19.

The control may likewise be carried out in 20 the known manner by a seam feeler, which, upon coming into contact with the seam of a wrongly placed cigarette closes the circuit for the electro-magnet 19. However, it is of course possible both in the case of direct observation and in 25 the case of observation by means of a photo cell or by means of a seam-feeler or the like to replace by a mechanical control the electric control obtained with the electro-magnet 19, by arranging for the above-mentioned means of control 30 to release a mechanical relay which brings the lever 15 into its neutral position. It will generally be sufficient if a wheel with turning pins 9 is provided only on one side of the chain 1, as shown in Fig. 2.

If necessary, however, such devices can also be arranged on both sides; as, however, the action is a comparatively gentle one, unilateral action suffices. Instead of the revolving wheel provided with the turning pins, it is also pos- 40 sible to provide for example an endless chain carrying the turning pins, this chain being moved forward at a speed corresponding to the revolution of the wheel 4. The pins 7 or pins 9 can, however, also be controlled by a crank or 45 eccentric motion.

In the form of execution shown, the stops for turning the cigarettes cross the path of the latter in the upward direction. It is, of course, also possible to arrange the conveying means for 50 the stops and allow it to rotate in such a way that it crosses the path of the cigarette in the downward direction, that is, it depresses the side of the cigarette which engages with the stops, and thus raises the opposite side.

We claim:—

1. In combination with a conveying device feeding parallel obliquely located cigarettes and similarly shaped articles of manufacture onto packing boxes or the like, a reversing device for the respective articles of manufacture which are lying on the wrong side, said device comprising a movable stop adapted to be moved into the path of the respective article and to contact with the one edge of the article when in its operative position, and means for moving said stop, during its operation, in a curved path intersecting the path of the article to be turned and having a component in the direction of the path of the article.

2. In combination with a conveying device feeding parallel obliquely located cigarettes and similarly shaped articles of manufacture onto packing boxes or the like, a reversing device for such of the respective articles of manufacture

- which are lying on the wrong side, said device comprising a plurality of stops adapted to be moved onto the path of the respective articles and to contact with the one edge of the article 5 when in their operative position and a conveying member carrying said stops, said member being adapted to move said stops in a curved path intersecting the path of the article to be turned and having one component in the direction of the 10 curved path and another component in the direction crossing the curved path.
3. In combination with a conveying device feeding parallel obliquely located cigarettes and similarly shaped articles of manufacture onto 15 packing boxes or the like, a reversing device for the respective articles of manufacture which are lying on the wrong side, said device comprising a plurality of stops adapted to be moved onto the path of the respective articles and to contact 20 with the one edge of the article when in their operative position, pivots to which said stops are eccentrically fixed, a revolving drum on which said pivots are eccentrically mounted at equal distances from one another, two additional lugs on each of said pivots, two members lying in the path of said lugs during the revolution of said drum, and one being adapted to turn the pivots 25 into the active position and the other to turn them into the neutral position, and a controlling device adapted to put one of said members out of action.
- on crossing the conveying device for the cigarettes pass between two cigarettes, whereas in the other position they engage a cigarette and turn it.
4. In combination with a conveying device feeding parallel obliquely located cigarettes and similarly shaped articles of manufacture onto packing boxes or the like, a reversing device for the respective articles of manufacture which are lying on the wrong side, said device comprising 5 a plurality of stops adapted to be moved onto the path of the respective articles and to contact with the one edge of the article when in their operative position, pivots to which said stops are eccentrically fixed, a revolving drum on which 10 said pivots are eccentrically mounted at equal distances from one another, two additional lugs on each of said pivots, two members lying in the path of said lugs during the revolution of said drum, and one being adapted to turn the pivots 15 into the active position and the other to turn them into the neutral position, and a controlling device adapted to put one of said members out of action.
